CONFECTION OR THE LIKE

Isadore Herman, New Kensington, Pa.

Application October 23, 1956, Serial No. 43,494

Term of patent 14 years

(Cl. D82—2)

Fig. 1.

Fig. 2.

Figure 1 is a front view of a confection or the like embodying my invention; and

Figure 2 is a side view of the confection or the like shown in Figure 1.

The characteristic feature of the design resides in the projection of the nose and mouth elements which is most clearly shown in Figure 2 in relation to and association with the other portions as shown. The drawing is toned to show contrasting appearance.

I claim:

The ornamental design for a confection or the like, as shown and described.
